UNITED STATES PATENT OFFICE.

SAMUEL FOSTER, OF CHICAGO, ILLINOIS, ASSIGNOR TO FREDERICK F. HAWKS, OF SAME PLACE.

DESIGN FOR A LAMP-BODY.

SPECIFICATION forming part of Design No. 33,502, dated November 6, 1900.

Application filed September 17, 1900. Serial No. 30,359. Term of patent 7 years.

To all whom it may concern:

Be it known that I, SAMUEL FOSTER, a citizen of the United States, residing at Chicago, in the county of Cook and State of Illinois, have invented and produced a new and original Design for Lamp-Bodies, of which the following is a specification, reference being had to the drawing forming a part thereof.

The accompanying drawing illustrates a lamp embodying my design.

As shown in the drawing, the leading or material features of my design lie in the conformation and configuration of a lamp-body.

A is the body portion, substantially globular in its general outline, and A' a base for supporting the globular body portion. A raised peripheral bead A² extends horizontally around the body portion, and at the top of the latter the stem A³ is placed.

A⁴ is a valve on one side of the body portion A.

The arms B extend upward and slightly outward from the upper side of the body portion, being secured to the latter by means of the enlarged portions B'. The upper ends of the arms B curve inward and face each other.

A scroll C in arch form unites the two upper ends of the arms B. Said scroll is made in ring form at its upper middle portion.

I claim as my invention—

The design for a lamp-body, substantially as herein shown and described.

SAMUEL FOSTER.
